UNITED STATES PATENT OFFICE

OTTO S. FLATH, OF CHICAGO, ILLINOIS

CONCRETE CRIBBING

Application filed February 10, 1927. Serial No. 167,086.

My invention relates to reenforced concrete cribbing employed in the construction of retaining walls more especially intended for supporting embankments or "fills" 5 where construction of the ordinary retaining wall is impracticable.

One object of my invention is to provide an economical cribbing composed of a few standardized units of such formation as to 10 be easily transported and assembled and which will readily adapt themselves to varying conditions, without requiring special skill in assembling.

A further object of my invention is the 15 provision of units adapted to interlock with each other, thereby eliminating the necessity for cementing or grouting as well as obviating the necessity for a preliminary tying of the various units together during the construction of a retaining wall; the various 20 units providing a flush relation between stretchers and headers at the front of the cribbing, while at the same time providing for the use of concrete slab units held in 25 place by the superposed stretchers whereby the interstices between the various courses are closed and filtering of the "fill" therethrough prevented.

These objects and the advantages will be 30 readily comprehended from the detailed description of the accompanying drawings, wherein—

Figure 1 is a perspective view of a portion of cribbing composed of my improved units.

Figure 2 is a perspective view of portions of the type of stretchers shown in Figure 1, illustrating the application of a filler slab or unit arranged intermediate of the headers.

Figure 3 is a perspective view of a portion 40 of cribbing composed of a modified form of stretcher and header units.

Figure 4 is a plan view of a portion of cribbing composed of my improved stretcher and header units shown in Figure 1.

Figure 5 is a sectional elevation of the 45 cribbing shown in Figure 4, illustrating the method of supporting a "fill".

Figure 6 is a perspective view of portions 50 of modified forms of stretchers, illustrating

the application of a modified form of filler slab.

In the particular exemplification of the invention as illustrated in Figures 1, 4 and 5, the cribbing comprises a plurality of uniform 55 units formed to provide an interlocking relation with each other which enables the cribbing to withstand the compression and lateral strains encountered in supporting embankments or "fills", and at the same time a 60 cribbing which will adjust itself without rupture or injury.

The cribbing disclosed in these figures consists of the units shown in Figures 15 and 16 of my previous application Serial No. 65 78,503; this application therefore in part covering subject-matter taken from said application Serial No. 78,503.

The cribbing of these figures consists of a 70 plurality of headers 15 and a plurality of stretchers 16 arranged in superposed relation at the ends of the headers.

The headers and stretchers are preferably 75 of reenforced concrete and of a predetermined more or less uniform length.

The stretchers 16 have what may be termed the inner or rear face provided with the vertically disposed portions 17, 17 constituting what may be termed longitudinal ribs of comparative width. That is to say, the rear side 80 of the stretcher 16 is of greater vertical width than the front side of the stretcher; the forward portions of the superposed stretchers being adapted to receive the ends 18 of the

headers 15 which are rectangular in cross-section and which at a proper distance removed from the immediate end and on opposite faces are each channeled at 19 to a width 85 and depth corresponding with the width and height of the rib portions 17 of the stretchers.

In this construction, it is apparent that the bearing surfaces at the front sides of the stretchers and at the front ends of the headers are of comparatively great dimensions. 90 These wide bearing surfaces shown in Figure 1 are adapted to take care of the compression shearing strains to which the front ends of the headers are subjected by the downward and outward pressure of the fill and any 95

100

tendency of breakage at the ends of the headers will be prevented.

Where it is desired to fill in the space between the different courses of stretchers at points intermediate of the headers, this may be accomplished by the employment of the precast slabs or blocks 20 shown in Figure 2. The slab 20 on one of its vertically disposed faces intermediate of the top and bottom is provided with a projection or rib 21 of thickness corresponding with the distance or interstice between the adjacent superposed stretchers. The laterally disposed rib portion 21 is inserted between the superposed stretchers with the body portion of the slab or block 20 arranged in lapping relation with the inner face of the stretchers. This will prevent displacement of the slab or filler block by the outward pressure of the fill. The elements or units 20 may be of length to correspond with the standard or usual distance between the respective rows of headers; or they may consist of smaller units of uniform block size and arranged end to end to fill in the interstices between the different courses of stretchers intermediate of the different rows of headers.

With the units or elements formed as shown in Figures 1 and 2 and arranged in proper assembled relation as described, it is apparent that wide bearing surfaces are provided between the various elements and that the interlocking relation between the stretchers and headers is arranged at a suitable distance removed from the immediate ends of the headers so as to provide comparatively wide shoulders or faces at the ends of the headers which will not be sheared off by the downward and laterally outward compression strains.

It is usual in the placing and assembly of the units to place a sufficient number of headers 15, substantially at right angles to the embankment or "fill" and in order to resist the compression strains, especially where the "fill" is to support railroad tracks as shown in Figure 5, the headers 15 are also arranged in courses forward of each other in order that proper anchorage may be provided; that is to say headers are arranged at what may be termed the inner side of the cribbing as shown at 15^a, in Figure 5, at right angles to the "fill" and in predetermined lateral spaced relation as shown in Figure 4, after which a second row of headers is arranged forward of the first mentioned row with the rear ends of the headers of the forward row arranged in lateral lapping relation as shown in Figure 4 at 22. After a sufficient number of headers have been placed as previously stated, the stretchers 16 are then arranged longitudinally of the "fill", with their ends resting on the ends of the headers, namely with the ribs 17 of the stretchers disposed in the grooves or channels 19 of the adjacent headers, while the forward longitudinal edge of each stretcher ex-

tends flush with the forward ends of the headers, the head 18 of the headers being of longitudinal dimensions equal to the width of the stretchers forward of the ribs 17. The headers and stretchers are preferably all formed of more or less uniform length in order that they may be readily handled; and the headers are preferably of a width to permit the ends of two aligned stretchers to be arranged in abutting relation in the groove or channel 19 of a header where the cribbing or wall is of some length, as indicated in dotted lines at 23 in Figure 4. The cribbing may be composed of any suitable number of rows of headers and stretchers, with the rows toward the inside of the "fill" being of less height than the outside row of stretchers see Figure 5, as is usual in the construction of retaining walls of the type in question. After the first rows of headers and stretchers have been laid as described, it is apparent that the succeeding courses of headers and stretchers are then arranged in like manner on top of the first course and so on until the retaining wall or cribbing has reached the desired height.

In Figure 3 I show a modification of the headers and stretchers.

The headers 24 at a predetermined distance removed from the ends are channeled or grooved on the upper and lower faces as shown at 25, for the purpose of receiving the ribs 26 of the stretchers 27; the ribs 26 being substantially like the ribs 17 of the previously described construction, Figures 1 and 2.

The immediate ends of the headers 24 are transversely chamfered as shown at 28 across the upper and lower faces, to a width and depth corresponding with the vertically disposed ribs 29 along the longitudinal edges—at top and bottom—of the stretchers 27. This provides the stretchers 27 with a longitudinal channel 30 throughout its length, which receives the portion of the headers intermediate of the channel 25 and the chamfer 28, so that an interlocking relation between the stretchers and the ends of the headers is provided.

It is apparent that where it is desired to close the openings between the superposed stretchers, this may be accomplished by employing the slabs 20 shown in Figure 2, which are adapted to extend merely between the different rows of headers as previously stated and arranged on the inside of the stretchers.

On the other hand, this may be accomplished by employing the type of slab shown at 31 in Figure 6 and employing stretchers substantially similar to the stretchers 16 shown in Figures 1 and 2. As the slabs 31 are of rectangular shape without the ribs 21 shown in Figure 2 and are intended to be employed at what may be termed the outer side of the cribbing, the stretchers 32, on their upper and lower faces are shown pro-

vided with longitudinal grooves 33 of sufficient depth and width to receive the longitudinal edges of the slabs 31 as shown; the grooves 33 being arranged forward of the vertically disposed longitudinal ribs 17.

5 It will be understood that when stretchers 32 and the filler members or slabs 31 are employed, headers like those shown at 15 in Figure 1 are to be used. The slabs 31, like 10 blocks or slabs 20, are applied before each superposed stretcher is put into place.

What I claim is:

1. Cribbing of the character described, composed of concrete units constituting 15 headers and stretchers arranged in superposed courses and filler elements, the headers being formed with transverse channels at a distance removed from the ends corresponding to the width of the main body portion 20 of the stretchers, the top and bottom faces of the stretchers being provided at the inner longitudinal edges with wide vertical extensions of width substantially equal to the width of the outer forward main body 25 portion and equal in width and depth to said channels in the headers to permit the extensions and main portion of the stretchers to lie flush with the tops and bottoms of the headers, while the filler elements are formed 30 with flat top and bottom surfaces adapted to be disposed intermediate of the vertical extensions of the different courses of stretchers so as to take compression strains at points intermediate of the lapping points of the 35 headers and stretchers, the outer longitudinal sides of the elements being provided with vertical extensions disposed above and below the top and bottom surfaces of said elements and adapted to lap the vertical faces 40 of the superposed stretchers.

2. A cribbing composed of a plurality of precast concrete units comprising headers, stretchers and filler elements, the headers at a distance from the ends corresponding to 45 the width of the main body portion and on the top and bottom faces being transversely channeled to a uniform width and depth, the stretchers on their top and bottom faces and at the inner longitudinal sides 50 being provided with vertically disposed wide flat faced portions corresponding in width and depth to and adapted to seat in the channels of the headers to provide interlocking relation against movement of the stretchers 55 lengthwise of the headers, the filler elements being formed to fit between the superposed stretchers intermediate of the lapping points of the headers and stretchers and prevent 60 movement of the elements transversely of the stretchers.

3. A cribbing composed of a plurality of precast comparatively wide concrete units constituting headers and stretchers arranged in lapping relation with each other, the 65 stretchers at their inner rear longitudinal

sides being provided with flat vertically disposed extensions on the upper and lower faces and of width substantially equal to the width of the forward main body portion, while the headers on their top and bottom 70 faces at a distance removed from their ends equal to the width of the forward main body portion of the stretchers are provided with transverse channels corresponding in width and depth to the width and height of the extensions on the inner longitudinal sides of the stretchers to permit the main body portion and the extensions of the stretchers to lie flush with the tops and bottoms of the 75 headers.
